JOHN HENRY BLACKBURN, OF PRESTON, AND WILLIAM EDWIN BANCROFT, OF ACCRINGTON, ENGLAND, ASSIGNOR TO HOWARD & BULLOUGH LIMITED, OF ACCRINGTON, ENGLAND

RING FOR THE UNWINDING OF YARN FROM YARN CONTAINERS IN CABLE-CORD FRAMES OR OTHER TWISTING OR DOUBLING FRAMES

Application filed November 8, 1929, Serial No. 405,682, and in Great Britain December 12, 1928.

The invention relates to frames for the manufacture of cable cord, and to the means adopted for unwinding the plied but untwisted yarns from yarn containers prior to the yarn having put therein the first twist as understood; but said invention is also applicable to other types of twisting or doubling frames.

In all such frames it is usual for each 10 yarn-container to rest upon a spindle mount, said spindle being driven by bands connecting the revolving tin roller with the wharve on said spindle or mount.

About the yarn container named is also 15 situated the ring carrying the usual traveller through which passes the yarn to be treated or twisted. Said ring however is fixed in position.

It is very desirable in the manufacture of 20 cable cord that the twist be of uniform character, and be produced in a positive manner or so that the twists shall commence in unalterable manner at a given point relatively to the yarn-container, for example, and not 25 before. Such a provision tends to prevent that chafing of the yarn which occurs in those cases where a partial twisting of the yarn takes place before the actual twisting operation is supposed to happen, or commence.

According to our invention, instead of a 30 ring which is fixed in position, we provide one which is revolvable; and free to run around the same is a traveller through which the yarn passes. That is to say said traveller 35 operates merely or largely as an unwinding device for unwinding yarn from the container in a cable cord-making frame. In this way the plied but untwisted yarn is capable of being supplied or brought to a particular 40 position before the first twist of the same commences. The traveller is carried round to a certain extent, but the drag exerted between it and the yarn passing therethrough operates to make it travel at a speed suitable 45 for unwinding purposes referred to.

With reference to the accompanying drawings, Fig. 1 is a sectional elevation showing a yarn-container or bobbin and adjacent parts arranged according to a form of our 50 invention. Fig. 2 shows on an enlarged

scale an upper portion of said Fig. 1, while Fig. 3 shows the same portion but at right angles to Fig. 2.

Fig. 4 is a plan view of the top of Fig. 2.

Fig. 5, on a similar scale to Figs. 2, 3 and 55 4, shows a portion of Fig. 1 at and about the position of the ring and traveller thereon.

Fig. 6 is a plan view of Fig. 1.

Fig. 7 is a modification of the lower part 60 of said Fig. 1. *a* is the yarn container (the yarn thereon not being indicated) and *b* is a ring about the upper part of the same container on which ring is a traveller *c*. Yarn indicated at *d* is shown passing through said traveller from the bobbin *a* to a point above. Said yarn originally consists of several plied 65 but untwisted strands.

The ring *b*, according to our invention, is 70 here attached to a tubular member *e* connected to a perforated base part *h* which is perforated to receive the spindle *m* on a mount or boss *k*. The tube *e* is thus arranged fast to the spindle, and moves with it. The tube *e* is also attached to a frame-like member 75 *o*, the upper extended part of which at *r* having a central vertical aperture therethrough, and side passages, guides or holes leading into the same. The manner in which the yarn passes through said apertures determines the amount of drag desired. 80

In Fig. 1 the yarn *d* is shown threaded out and in of these side passages, and then to a guide roller or rod *s* above. It will be seen that as the tube *e* and ring *b* are carried round by the spindle *m*, actual twisting takes 85 place between the upper part *r* of the framing named, and a point beyond the rod *s*, such as at a pair or nip rollers *t*. Below the part *r*, through the traveller, and from the traveller to the bobbin, the yarn is in its un- 90 twisted state. On the other hand, said traveller is free to move on the ring according to the drag put upon it, and said traveller operates to unwind the yarn from the container *a*, also there is not the tendency to 95 partially twist the yarn as between the traveller and said container, such as often occurs with the use of a fixed ring. In Fig. 7, the tubular member *e* is attached to a base part *h*, formed with an annular cavity at *u* in 100

pulley-groove manner. The tube and ring may thus be positively driven at a correctly-timed speed from an outside mechanism in connection with groove u by a band for the purpose. In which case the contact between h^1 and mount k would be merely frictional.

We claim:

1. In cable cord frames and other like twisting or doubling frames, a revoluble ring,
10 a movable traveller on said ring, a yarn-container within said ring, from which yarn passes to and through said traveller, a mount about said yarn-container to which said ring is connected, a spindle passing through said
15 yarn-container with which said mount is revolved, an extension of said mount, yarn guides in said extension through which yarn from the traveller and container passes, whereby a positive twist is put into the yarn
20 between said guides and a determinable point beyond, and whereby the traveller named operates merely to unwind the yarn from the container aforesaid.
2. In cable cord frames and other like
25 twisting or doubling frames, a revoluble ring, a movable traveller on said ring, a bobbin within said ring, from which yarn passes to and through said traveller, a mount about said bobbin to which said ring is connected,
30 a spindle passing through said bobbin with which said mount is revolved, an extension of said mount, yarn guides in the form of apertures in said extension through which yarn from the traveller and bobbin passes,
35 whereby a positive twist is put into the yarn between said guides and nip rollers beyond, and whereby the traveller operates merely to unwind the yarn from the bobbin aforesaid.
